UNITED STATES PATENT OFFICE.

PHILLIP R. KRAMER, OF BAY CITY, MICHIGAN.

MAGAZINE RIFLE.

Application filed June 21, 1926. Serial No. 117,323.

This invention relates to rifles and particularly to a slide or pump action rifle.

One object of the invention is to design a sturdy and practical well balanced rifle having but few small working parts.

Another object is to provide a rifle which can be assembled without the aid of tools, and in which the action can be removed or replaced in the frame work as a unit for cleaning, inspection, or any other desired purpose.

A further object is to design a rifle in which the action is automatic, or self-acting to supply shells to the barrel, set the hammer and eject the cartridge after it has been discharged.

The above and other objects will appear as the specification progresses, reference being had to the accompanying drawings in which I have shown the preferred embodiment of my invention, and in which like reference numerals indicate like parts throughout the several views thereof.

In the drawings.

Fig. 1 is a part sectional side view of my improved rifle.

Fig. 2 is also a part sectional side view thereof, the mechanism being shown in a different position.

Fig. 3 is an enlarged detail side view of the rifle magazine.

Fig. 4 is a vertical sectional view thereof.

Fig. 5 is a transverse sectional view taken on the line 5—5 of Fig. 3.

Fig. 6 is an end view of the magazine.

Fig. 7 is a transverse sectional view through the rifle magazine showing the cartridges in place ahead of the feed wing.

Fig. 8 is a side view of the shell regulator.

Fig. 9 is an end view thereof.

Fig. 10 is an assembly side view of the breech block carrier, hammer and hammer seat.

Fig. 11 is a top plan view thereof.

Fig. 12 is an end view of the breech block carrier.

Fig. 13 is a transverse sectional view thereof taken on the line 13—13 of Fig. 10.

Fig. 14 is a side view of the breech block.

Fig. 15 is an end view.

Fig. 16 is an opposite end view.

Fig. 17 is a side view of the timer lever dog and stop collar.

Fig. 18 is a front view thereof.

Fig. 19 is a side view of the breech block carrier latch.

Fig. 20 is a top plan view thereof.

Fig. 21 is a front form view of the hammer seat or dog.

Fig. 22 is a sectional edge view thereof.

Fig. 23 is a side view of the operating hand stock sleeve.

Fig. 24 is a side view of the hook shaped tilting member.

Fig. 25 is a front view thereof.

Fig. 26 is a side view of the hammer spring guide and support.

Fig. 27 is a top plan view thereof.

Fig. 28 is a part sectional view of the feed wing sleeve and tensioning mechanism.

Fig. 29 is an end view.

Fig. 30 is a transverse part sectional view having lugs on the ends of the sleeve and which form the clutch.

Referring now particularly to the drawings in which I have shown the preferred embodiment of my invention, the numeral 1 indicates a combined magazine and breech casing shaped as clearly shown in Figs.

3, 4, 5, and 6 of the drawing, the one 80 end being threaded as shown at 2, and is adapted to receive the threaded end 3 of a barrel member 4 in the usual manner.

An opening 5 is provided in the top of the magazine, and spaced apart ribs 6 are provided on the interior thereof, a bearing 7

being formed intermediate the length thereof, and grooves 8 are provided in the back end for attaching a hand stock thereto.

A breech block carrier 9 shown in Figs. 90

10 and 11, is slidably mounted in the magazine, the top and bottom being cut away for a portion of its length, the rear end terminating in a squared block 10 having an opening 11 bored therethrough, the upper 95 portion of said block having an elongated slot 12 therein, the sides being milled out as

shown at 13 to accommodate the hammer seat or dog 14 which straddles said block, and is pivotally connected thereto by means 100

of the pin 15, a head 16 being formed on the top of said hammer seat for engagement by the hammer 17 which is pivotally connected to the block by a pin 17^a, and

which is provided with a bifurcated center 18 105 to which one end of the hammer spring guide 19 is connected by the pin 19^a, the opposite end being slidably mounted in an

opening 20 provided in the transversely disposed pin 21, a coiled spring 22 being interposed between said pin and the head of the hammer spring guide for properly tensioning said hammer.

A breech block 23 is mounted and tiltingly secured in the breech block carrier, and is formed as clearly shown in Fig. 14 of the drawing, a blind set screw 28^a securing the block in the carrier, and being sufficiently loose to allow it to tilt. A boss 24 is formed on the top of the breech block, and is seated in the opening 5 in the magazine frame when the mechanism is in firing position, the front end being turned to fit the carrier proper, the rear end having a downwardly projecting inclined lug 25 formed integral therewith, and for a purpose to be presently described.

20 A hanger 26 is secured to the underside of the rifle barrel, and an operating hand stock sleeve 27 is slidably mounted therein, one end being formed with an enlarged head 27^a, transversely disposed openings 28 extending therethrough, and receive screws (not shown) which extend through the wood of the forestock 29, a rod 30 is mounted in this sleeve, said rod extending through the cartridge magazine and breech block carrier, 30 and a stop collar 31 is mounted on the end thereof, the front end being threaded to receive a lock nut 32.

A cylindrically shaped member 33 forms a closure for the front end of the cartridge magazine, being secured in position by means of the small screws 33^a, the reduced end 34 of said member projecting outwardly, and is mounted on a sleeve 35 which is grooved as shown at 36, a locking member 37 being secured to the reduced end 34 by means of screws 38, the end having a head 39 which engages in the groove 36 for holding it in position, the end of said member 35 being preferably fluted so that it can be 45 turned by the operator to release the tension on the cartridge feed wing, so that the cartridges may be easily removed from the magazine when desired. The forestock 29 being slidably mounted on said member 27.

50 A sleeve 40 is mounted on the rod 30 within the magazine chamber and is formed with shoulders 40^a and 40^b respectively, of different diameters, a short dowel pin 41 projecting from the shoulder 40^a and is adapted to 55 engage a suitable opening provided in the bearing 7 and prevent the rotation of the sleeve. A larger sleeve 42 is placed over this sleeve 40, the one end being mounted on the shoulder 40^b, the opposite end having a reduced opening 42^a in which the reduced end 60 of the sleeve 40 is mounted, a jaw 43 being formed on said end as clearly shown in Fig. 28 of the drawing. Openings 44 and 44^a are formed in the shoulder 40^b and sleeve 42 respectively, and receive the ends of a spring

member 45 which is mounted on the sleeve 40 for properly tensioning the device, a feed wing 46 being secured to said sleeve 42 within the cartridge magazine, and serves to force the cartridges up and against the breech block carrier as required.

A hook shaped member 46^a is pinned on the rod 30, and is provided with an opening 47 which is adapted to receive the lug 25 formed integral with the breech block when the forestock is actuated, a spacing lever 48 being pivotally secured to the bottom thereof, and is provided with a jaw 48^a for engaging and spacing the breech block carrier therefrom, a flat spring 49 being provided for forcing the jaw into position, and from which it is disengaged by the leg 17^b of the hammer, as the hammer is released by pulling the trigger 50 for actuating the firing mechanism.

85 A cartridge regulating member 51 shown in Figs. 8 and 9, is secured to the bearing 7 by means of screws 52, and is formed with spaced apart outwardly projecting fingers 53 on which the breech block carrier rests, and these fingers regulate the feed of the loaded cartridges to the magazine (as the breech block is actuated), preventing the entry of a loaded cartridge until the discharged cartridge has been ejected.

90 A timing lever dog 55 is formed integral with the stop collar 31 and is provided with a head 59 which normally engages a trigger lever 56, and when the mechanism is in firing position, this lever is pivotally connected 100 to the stock frame 57 by the pin 58, the free end of the lever being provided with a lug 56^a which engages the dog 60, which is in turn pivoted to the breech block carrier at the point 61, the upper end of said dog engaging the socket 62 formed in the one leg of the hammer seat, the free end of the lever engaging a pin 63 provided in the stock frame, and which limits the upward movement of the lever, a flat spring 64 serving 110 to tension the lever at all times.

115 The trigger 50 is connected to said lever 56 as shown, and when the trigger is actuated, the dog will be released, this in turn allows the hammer seat to swing back, and the hammer, actuated by the hammer spring guide, swings up and strikes the firing pin 65 discharging the cartridge, as the lever member 48 is in the path or arc of travel of the ends of the hammer legs 17^a they automatically force it downwardly, disengaging it from the block 10, the operator then actuates the fore stock forcing it back, and with it the rod 30, the member 46^a moves with the rod, the lug 25 engaging the opening therein, pulling it down, and the lug 24 out of the opening in the magazine cylinder, the hammer legs 17^b engage and ride on the ribs 6 which are provided on the interior of the magazine, during the rearward movement of 120

the mechanism preparatory to being again reset, continued movement butts the member 46^a against the shoulder of the breech block carrier. The initial rearward movement of the rod 30 also separates the stop collar 31 from the end of the breech block carrier, and the jaw 66 of the latch 66^a, which is pivoted to the breech block carrier by the pin 67, engages the stop collar 31, and spaces them from each other, a flat spring 68 serving to tension said carrier latch which is offset as shown, and which is released by engagement with the ribs 6 on the return movement of the mechanism the hammer legs 17^a ride on these ribs during this return movement, the head of the hammer engaging the head 16 of the dog 14 and being automatically locked in position by engagement of the dog 60 with the lug 56^a of the trigger lever 56, the extreme forward movement moving the hammer legs 17^a ahead of the ribs 6 a distance sufficient to permit them to swing down and disengage the lever 48 when the trigger is actuated.

25 The firing pin and cartridge extractor are of the conventional design and form no part of the present invention and are therefore not shown or described in detail.

An opening 69 is provided in the magazine 30 to allow for the loading and ejection of the discharged cartridges, and a door 70 forms a partial closure therefor, lugs 70^a being cast integral with the door, and a suitable opening is provided in the lugs to receive the pin 71 which passes therethrough, and also through the boss 72 on the wall adjacent the door opening, a blind screw 73 serving to hold said pin in position, these lugs being shaped so that when the door is in open position, the distance between the lugs and the sleeve 42 will be slightly less than the diameter of the cartridge, making it necessary to slightly spring the sleeve 42, forcing a cartridge into the chamber, this prevents cartridges in the magazine being ejected when the door is open, and facilitates the loading, because as the feed wing is forced around by additional cartridges, the tension on the wing is increased accordingly, in the construction as shown this tension is taken by the lugs, excepting when the operator forces the cartridge past the lugs, the door swinging slightly as this is done, when the door is closed the passage is then of the regular size to accommodate the cartridges, and the fingers on the cartridge regulator prevent the cartridges slipping out of the rifle.

55 A latch is also provided for holding the door in closed position, an elongated boss 74 being formed on the door and is bored to receive a pin 75 on which a spring 76 is mounted, a slot 77 being formed in said boss, and a latch member 78 projects therethrough, the inner end being secured to the pin 75, a boss 79 being formed on the wall of the mag-

azine and is drilled to receive the end of the pin for locking.

I wish to direct particular attention to the fact that the door does not entirely cover the opening in the magazine as sufficient space must be left to accommodate and admit of the passage of the ejected cartridges.

From the foregoing description it will be obvious that I have perfected a very simple, economical and practical rifle of few parts, and from which the action can be removed as a unit for any desired purpose.

What I claim is:

1. A magazine rifle comprising a frame, a manually actuated rod journaled therein, a breech block carrier reciprocatingly mounted in the frame, a breech block mounted in the carrier and means on the rod engaging said breech block for moving it downwardly and rearwardly into and out of engagement with the frame.

2. A magazine rifle comprising a frame, a manually actuated rod journaled therein, a breech block carrier slidably mounted in said frame, a breech block in the carrier and engaging the frame and means on the rod adapted to engage said breech block for moving it into and out of engagement with said frame.

3. A magazine rifle comprising a frame, a breech block carrier reciprocatingly mounted therein, a breech block mounted in the carrier and formed with a lug which engages an opening in the frame, a manually actuated member journaled therein, and means on said member adapted to engage said breech block for moving it into and out of engagement with said opening.

4. A magazine rifle comprising a frame, a breech block reciprocatingly mounted therein, a cartridge regulator below said breech block, a manually actuated rod journaled in the frame, a spring tensioned feed wing also mounted in the frame and adapted to feed cartridges to the regulator as the mechanism is actuated.

5. A magazine rifle comprising a frame, a breech block reciprocatingly mounted therein, a cartridge regulator secured in the frame below the breech block and provided with spaced apart fingers, and spring tensioned means for feeding the cartridges against the fingers.

6. A magazine rifle comprising a frame having a cartridge chamber integral therewith, a manually actuated rod extending through said chamber, a spring tensioned sleeve mounted thereon, and provided with a feed wing, and a cartridge regulator secured in the frame and provided with spaced apart fingers for regulating the cartridges fed to the rifle barrel.

7. A magazine rifle comprising a frame having a cartridge magazine formed therein, an opening in the side wall thereof, a

- door forming a partial closure for said opening, a manually actuated rod passing through said chamber, a spring tensioned sleeve mounted therein, a feed wing fixed to the sleeve, and lugs on the door adapted to restrict the passage between the door lugs and the sleeve when the door is in open position.
8. A magazine rifle comprising a frame having a cartridge magazine, a breech block carrier, a bracket formed on the interior of said frame, a bearing, a rod journaled therein, a cartridge regulator secured to the bracket, a breech block tiltingly mounted in the carrier, and fingers on the regulator for regulating the cartridges fed to the rifle barrel when the breech block is actuated.
9. A magazine rifle comprising a frame having a cartridge magazine formed integrally therewith, ribs formed on the interior thereof, a breech block carrier and breech block reciprocatingly mounted in the frame, a hammer mounted on the breech block carrier and adapted to engage said rib to set the hammer when the breech block is actuated.
10. A magazine rifle comprising a frame having a cartridge magazine, a manually actuated rod projecting therethrough, a breech block carrier mounted thereon, and a breech block tiltingly mounted in the carrier and formed with a downwardly projecting lug, a hook member secured on the rod, and adapted when the rod is actuated to engage the lug on the breech block for moving it downwardly and rearwardly in the frame.
11. A magazine rifle comprising a frame having a cartridge magazine, a longitudinally extending rod mounted therein, a breech block carrier mounted on the rod, and a breech block tiltingly secured therein and engaging an opening in the frame, means on the rod for engaging the breech block when the rod is actuated, and a spring tensioned feed wing mounted in the frame for forcing the cartridges out of the cartridge magazine.
12. A magazine rifle comprising a frame having a cartridge magazine, a barrel secured to the frame, a hanger secured to the barrel, a rod journaled in the hanger and
- frame, a forestock secured to the rod, a sleeve in the forestock, a lug on the end thereof, and a cylindrical member forming a closure for the end of the magazine and having an outwardly projecting reduced end mounted on said sleeve, a spring tensioned sleeve mounted in the cartridge magazine, and a lug on the end thereof adapted to form a clutch with the first mentioned sleeve.
13. A magazine rifle comprising a frame, a barrel secured thereto, a hanger on the barrel, a rod journaled in the frame and hanger, a breech block carrier mounted on the rod, a spring tensioned hammer seat and hammer mounted on said carrier, means on the rod for engaging the breech block when the rod is actuated, and ribs on the interior of the frame for setting the return movement of the carrier.
14. A magazine rifle comprising a frame, a manually reciprocated rod mounted therein, a breech block carrier mounted thereon, a breech block tiltingly secured in the carrier and engaging an opening in the frame, a hammer seat and hammer pivotally mounted on the carrier, a dog pivotally secured to the carrier and engaging said hammer seat, a trigger lever engaging said dog, and means on the rod adapted to engage and tilt the breech block to disengage it from the frame when the rod is actuated.
15. A magazine rifle comprising a frame having a cartridge magazine, a manually actuated rod passing therethrough, a spring tensioned sleeve mounted thereon, a feed wing secured thereto, a second sleeve on the rod directly adjacent the spring tensioned sleeve, and lugs on the ends of the sleeve to form a clutch to permit of manually relieving the tension on the feed wing for loading or removing cartridges from the chamber.
16. A magazine rifle comprising a frame having a cartridge magazine, a rod extending therethrough, a spring tensioned feed wing mounted thereon, a cartridge regulator secured in the frame and fingers on the regulator for regulating the cartridges fed from the magazine.

In testimony whereof I affix my signature.

PHILLIP R. KRAMER.
